Primary Examiner — Antoine Duval Davis(74) *Attorney, Agent, or Firm* — Foley & Lardner LLP(57) **CLAIM**

We claim the ornamental design for a cutting template, as shown and described.

DESCRIPTION

FIG. 1 is a perspective view of an embodiment of the claimed design; and,

FIG. 2 is another perspective view thereof.

Any portion of the article depicted in broken lines forms no part of the claimed design. Broken lines formed by equal length dashes show unclaimed subject matter. Broken lines formed of unequal length dashes (i.e., dash-dot) show boundaries between claimed and unclaimed portions of the design.
